UNITED STATES PATENT OFFICE.

HORACE GARST, OF DENVER, COLORADO.

BAG.

1,199,979.

Specification of Letters Patent.

Patented Oct. 3, 1916.

Application filed January 4, 1916. Serial No. 70,149.

To all whom it may concern:

Be it known that I, HORACE GARST, a citizen of the United States, residing at Denver, in the county of Denver and State 5 of Colorado, have invented certain new and useful Improvements in Bags, of which the following is a specification.

This invention relates to certain new and useful improvements in bags, its primary 10 object being to provide a bag of novel construction and attractive appearance which retains its shape when opened or closed, which when not in use may be reduced in size for the purpose of storing or packing 15 it in a small space, and which being composed of few parts may be economically produced.

With the above objects in view, my improved bag consists of a bottom member reinforced by suitable stiffening material, a collapsible circumferential wall member of sufficient rigidity to stand upright under normal conditions, and a top member provided with a mouth affording access to the 25 interior of the bag and with adjustable means for retaining said mouth in either the open or closed condition. The three members are fastened together by sewing and may be made of cloth or any other suitable 30 flexible material.

A slit formed in the top member of the bag provides the mouth which affords access to its interior and sets of normally aligned sticks concealed in pockets at opposite sides 35 of said slit, constitute the adjustable means by which the mouth is held in its open and closed conditions.

When the bag is open the sticks are relatively disposed to form a quadrangle which 40 affords ready access to the interior of the bag.

Strings are applied at the points of junction of the sticks of the two sets to secure the mouth of the bag in its closed condition, 45 and handles fastened to the top-member at opposite sides of the mouth provide ready means for carrying the bag or for opening and closing its mouth.

The bag may be made round, oval or square 50 in any desired size and of any flexible material and as such it is adapted for use of

travelers, shoppers or hunters as well as for the storage of toilet requisites and other small articles on desks and dressing tables.

In the accompanying drawings in the various views of which like parts are similarly designated, Figure 1 is a plan view of my improved bag in its closed condition, Fig. 2 a similar view of the bag with its mouth in the open position, Fig. 3, a section taken 60 along the line 3—3, Fig. 1, drawn to an enlarged scale, Fig. 4, a correspondingly enlarged transverse section taken along the line 4—4, Fig. 1, Fig. 5, a fragmentary sectional view of the bottom portion of the bag 65 showing a modified method of applying the reinforcement thereto, Fig. 6, a development of the single piece of material of which the top-member of the bag is composed, Fig. 7, a view of the piece shown in Fig. 6, after 70 it has been initially folded in the process of forming the top-member, and Fig. 8, a perspective view of the top-member folded in a condition ready for its connection with the other members of the bag. 75

Referring to the drawings by numerical reference characters, 2 designates the bottom member, 3 the circumferential-wall-member, and 4 the top-member of the bag.

The bottom-member in its preferred form, 80 is composed of two flexible sheets 23 sewed together around an interposed piece 24 of reinforcing material, such as fibroid, the contour of which determines the shape of the finished article. 85

The sheets between which the reinforcing piece is secured, are extended beyond the edge thereof to provide a flange 5 for fastening the bottom-member to the lower edge of the side or wall-member of the bag. This 90 last-mentioned member is made of two continuous flexible strips 6 stitched together as at 7 and sewed along the lower edges to the up-turned flange of the bottom member as shown in Figs. 3 and 4 of the drawings. 95

The two strips of which the wall-member is composed, render it sufficiently rigid to extend normally in an upright position, while at the same time it is flexible to the 100 extent that it may collapse when subjected to pressure.

The top-member of the bag is made of a single sheet of cloth or other flexible material the ends of which are connected and which is subsequently doubled to provide pockets 5 for the sticks which bind the mouth of the bag.

The material before being folded or connected is as shown in Fig. 6, cut in the form of two sections 8 of the general contour of 10 the finished bag, which are integrally connected at one of their ends as at 9 and which subsequently are also connected at their opposite ends by sewing, as at 10 in Fig. 7.

By folding the sheet formed and connected as hereinbefore described, so as to bring its edges along which it is doubled, together, and then bending its outer portions at an angle to the said edges as shown in Fig. 8, a top is produced which in contour 15 corresponds with the bottom-member of the bag and which has a slit 12 bounded by upturned flanges 13. The flanges 13 are stitched as at 14 to form pockets for the reception of four sticks 15 of substantially 20 equal length which define the mouth of the bag as hereinbefore explained.

The folded parts of the top-member are furthermore connected by rows of stitching 16 and the member is sewed at its outer 25 edge along the upper edge of the wall-member as shown at 17. To conceal the stitches which connect the top and bottom members of the bag with the wall-member, the edges of the latter are turned inwardly as shown in Figs. 3 and 4 of the drawings.

The sticks 15 placed in the pockets produced by the stitchings 14, are normally aligned in pairs in the upturned flanges at 30 opposite sides of the slit which constitute the mouth of the receptacle, as shown in Fig. 1, there being sufficient play between the ends of the sticks for their relative adjustment to form a quadrangle as illustrated 45 in Fig. 2.

At the points of juncture of the aligned sticks, cords 18 are attached to the flanges of the top-member for tying the mouth in its closed condition, and handles 19 made 50 of doubled strips of cloth are sewed to the top at points adjacent those at which the fastening cords are applied.

In bags of larger dimensions, the reinforcement of the bottom-member may be 55 made separate from and placed removably within the bag as shown at 20 in Fig. 5. By removing this reinforcement, a bag thus constructed may be collapsed and folded when not in use, and to still further reduce 60 the compass of the collapsed article the reinforcement may be made in sections as shown in the drawing.

From the above description, taken together with the drawings, the operation of

my improved bag will be readily understood without further explanation at this point, it being observed that by pressing the top and bottom members of the bag together, its normally rigid wall may be collapsed to reduce the size of the article when 65 not in use.

Having thus described my invention, what I claim and desire to secure by Letters-Patent is:

1. A bag comprising a bottom-member, 75 a top-member having a mouth provided by a reinforced slit, and a wall-member connecting the top- and bottom-members, the said wall-member being composed of a plurality of strips of flexible material stitched 80 together, whereby it is normally rigid and adapted to collapse when the top and bottom members are pressed together.

2. A bag comprising a bottom-member, 85 a top-member having a mouth provided by a slit, sets of normally aligned sticks at opposite sides of said mouth, and a wall-member connecting the top- and bottom-members, the said top-member being composed of a single piece of flexible material 90 cut and folded to the required shape.

3. A bag comprising a bottom-member, a top-member having a mouth provided by a slit, sets of normally aligned sticks at opposite sides of said mouth, and a wall- 95 member connecting the top- and bottom-members, the said top-member being composed of a single piece of flexible material cut and folded to the required shape and stitched to provide pockets for the said 100 sticks.

4. A bag comprising a bottom-member, a top-member having a mouth provided by a slit, sets of normally aligned sticks at opposite sides of said mouth, and a wall- 105 member connecting the top- and bottom-members, the said top-member being composed of a single piece of flexible material formed of two sections of the general shape of the finished bag, which are connected at 110 their opposite ends and folded to provide a pair of upturned flanges defining said slit and which are stitched to provide at the edges of said flanges, pockets for the said sticks.

5. A bag comprising an annular wall-member turned inwardly at its edges, a top-member having a mouth provided by a reinforced slit, and a bottom-member, the said top- and bottom-members being attached to 120 said turned edges of the wall-member.

6. A bag comprising a bottom-member, a top-member having a mouth provided by a slit, two sets of normally aligned sticks at opposite sides of said mouth, handles aligned upon the upper surface of said top-member 125 at opposite sides of said mouth and each composed of a strip of cloth bent upon

itself to provide a loop adjacent the mouth, and a wall-member connecting said top- and bottom-members.

7. A bag comprising a bottom-member composed of a sheet of flexible material, a top-member having a mouth affording access to the interior of the bag, and a wall-member connecting said top- and bottom-members, and a reinforcement loosely supported upon the upper surface of the

bottom-member and adapted to be removed from the bag through the mouth of its top-member.

In testimony whereof I have affixed my signature in presence of two witnesses.
